(57) **CLAIM**

The ornamental design for a clip-on face plate for swivel belt clip for cellular telephone, as shown and described.

DESCRIPTION

FIG. 1 is a perspective view of the clip-on face plate mounted on the swivel belt clip with the swivel belt clip for cellular telephone shown in phantom lines.

FIG. 2 is a perspective view of the clip-on face plate removed from the swivel belt clip with the swivel belt clip for cellular telephone shown in phantom lines.

FIG. 3 is a front elevational view of the clip-on face plate.

FIG. 4 is a rear elevational view of the clip-on face plate.

FIG. 5 is a right side view of the clip-on face plate (the left side view being a mirror image of the right side view).

FIG. 6 is a bottom view of the clip-on face plate; and,

FIG. 7 is a top view of the clip-on face plate.

The items shown in phantom lines form no part of the claimed design.
